BEDSPRING

Nathan C. Goldberg, New York, N. Y.

Application December 2, 1942, Serial No. 467,635

6 Claims. (Cl. 5—190)

The present invention relates to bed springs. More specifically, it relates to bed springs of the wire fabric type, wherein a mesh type wire fabric is supported in a bed spring frame by a plurality of coiled springs located at each end of the frame and secured at the opposite ends of the wire fabric.

One of the principal objects of the invention resides in the provision of a mesh fabric consisting of a multiplicity of generally longitudinal, flexible wire cables having clips to secure adjacent cables to each other in order to form the mesh fabric, together with means for protecting the ends of the cables so that they will not be exposed and cannot assume any position where they might catch or tear the mattress or linens placed on the bed.

A further object of the invention resides in the provision of a mesh fabric supported by a series of end springs as described above, together with a strain distributing member in the form of a transverse wire extending between all of the springs at one end of the bed, so that a strain exerted on one of the cables of the mesh fabric will not be entirely supported by the single spring to which that cable is attached, but will be distributed in progressively decreasing amounts to the adjoining springs on either side.

A further object of the invention resides in the provision of a strain distributing wire as above, together with a novel arrangement for shielding the ends of said wire within the convolutions of one of the coil springs, so that it cannot catch or tear the mattress or linens of the bed.

Another important object of the invention resides in the provision of a strain distributing wire extending between the individual coil springs at one end of the bed and formed to include a notch adjacent each spring in order to facilitate locating the spring and the cable ends of the wire fabric with respect to the strain distributing member.

Other objects will appear hereafter.

Referring now more particularly to the drawings attached to and forming a part of the present specification:

Fig. 1 is a fragmental plan view of a bed spring constructed in accordance with the teachings of the present invention.

Fig. 2 is an enlarged detail plan view of one end of one of the transverse supporting bands illustrated in Figure 1.

Fig. 3 is a detail sectional view taken substantially on the plane of the line 3—3 of Figure 2.

Fig. 4 is a detail fragmental plan view of a por-

tion of the bed spring shown in Figure 1, the coil springs illustrated therein being shown in section.

Fig. 5 is a fragmental plan view similar to Figure 4 and illustrating a modified embodiment of the strain distributing wire.

The form of bed spring illustrated in the drawings includes, in general, a pair of side frame members connected at two points intermediate the end frame members 12 by cross braces 13. The frame members 11, 12 and 13 serve to support metal fabric generally indicated by the reference number 14.

To this end the frame members 12 are each provided with a relatively thin spring anchor plate 15 secured to the frame 12 in any suitable manner, as for example, by wood screws 16 extending through the plates 15 and into the wooden frame members 12. The spring anchor plates 15 include a plurality of punched openings in which the anchor loops 17 of the individual coil springs 18 are secured. These springs in turn support the cables forming the mesh fabric 14.

The free ends of each of the springs terminates in a loop 19 and the entire group of springs at one end of the bed are operatively united by a strain distributing wire 21 extending from one side of the spring assembly to the other and through the loop 19 of each spring. The opposite ends of the strain distributing wire 21 are bent at a right angle to provide short leg portions 22. These leg portions 22 are telescoped within the convolutions of the end spring 18, so that no sharp edges of metal are left exposed and any danger of catching and tearing the mattress or bed linens placed on the spring assembly is eliminated.

The fabric 14 of the spring includes a number of longitudinal coiled wire cables, and, in the form of invention illustrated in the drawings, the number of longitudinal wires is exactly double the number of coil springs 18 at each end of the bed. The cables are brought together at each of the springs 18. These cables are joined by twisting into a "pigtail" 26 that is inserted within the convolutions of the spring, so that the sharp, loose ends of wire will not be exposed and so that the mattress and bed linens cannot be snagged or torn.

From an examination of Figure 4, it will be seen that one of the cables 25 of each pair is positioned above the strain distributing wire 21, and the other cable is positioned below this wire, so that each pair of cables forms a loop encircling and directly engaging the strain distributing wire

21. Similarly, the loop 19 of each individual spring is passed around the strain distributing wire 21 and through the loop between the cables, so that the spring, cables, and strain distributing wire are interconnected with each other and will act as a unit. In practice, this means that any load imposed on any one of the cables will principally be supported by the spring to which that cable is attached, but the strain distributing wire 21 will transmit a portion of the load to the adjoining springs on each side. The inherent flexibility of the wire 21 will result in a reduction of the strain on the more remote springs of the group, so that the closest springs bear the greatest part of the strain and the more remote springs receive a reduced share of the load. It will also be observed that in the event any of the springs 18 should become broken, none of the cables 25 will be released, since the cables 25 will still be secured to the wire 21 and any load imposed upon the cables will be distributed to the adjacent springs on either side of the broken spring.

It is contemplated that the strain distributing wire may be any one of several cross sections, but it is believed that the most satisfactory results will be obtained by the use of a round wire, since a wire of round cross section is equally flexible in all directions and will not be subject to any tendency to twist or buckle in response to forces acting on it.

In the modified form of the invention illustrated in Figure 5, the strain distributing wire 31 includes leg portions 32 arranged to extend into the springs 18 in the same manner as the leg portions 22 of the wire illustrated in Figure 4, but the wire is modified by the provision of a multiplicity of notches 33 to receive the end loops 19 of the springs 18. The general function of this form of invention is the same as that just described, but the notches 33 perform a useful function in assisting in locating the springs 18 along the wire 31 and in preventing any longitudinal shifting of the loops 19, with respect to the wire.

One of the transverse bands arranged to support the spring fabric is illustrated in Figures 2 and 3 of the drawings. In the illustrated embodiment of the invention, the spring fabric 14 is provided with two auxiliary supporting bands 35 located at positions approximately $\frac{1}{3}$ of the length of the bed from each end. These bands are supported by coil springs 36 carried by anchor screws 37, which are threaded into the side members 11 of the frame.

The supporting bands 35 are punched at 38 to provide ears 39 that are clinched to individual cables 25, so that they will be held in relatively fixed position with respect to the band 35, and flat wire links 40 are used to join adjacent pairs of cables and thus provide a mesh fabric. In the preferred construction of the spring, however, the three cables on each side of the bed are not secured directly to the band 35, but are secured at the opposite ends of the spring 36 by means of flat wire clips as illustrated in Figures 2 and 3. The extreme side cable is secured to the anchor screw 37 by means of a clip 41 and the second and third cables are secured between the inner end of the spring 36 and the end of the supporting band 35 by means of a similar clip 42. With this arrangement, the surface of the spring fabric 14 reaches the full width of the bed frame, and further, there can never be any interference between the cables of the supporting fabric and the coil springs 36, since cables of the

fabric do not cross the coil springs. This eliminates difficulties found in various prior-art structures wherein one or more wires of the fabric of the bed spring have been positioned above or immediately below the side coil springs, with the result that they become entangled to the coils of the spring, damage either the spring or mesh fabric, and thus impair the operation of the assembly.

10 From the foregoing, it will be apparent that by practicing the teachings of the present invention, a novel and highly useful bed spring assembly is provided that accomplishes the objects of the present invention in an efficient and economical manner, and by the use of a structure that is extremely simple, rugged in use, economical in manufacture, and well adapted to mass-production methods of manufacture.

While the present invention has been specifically designed for military use and is believed to be particularly well adapted to use on army cots and bunks, its utility is believed to extend to other fields, and it is accordingly requested that the scope of this invention be regarded as limited, 25 only by the terms of the appended claims.

Having thus described my invention, what I claim as new and desire to secure by Letters Patent is:

1. In a bed spring including longitudinal side 30 frame members and transverse end frame members, the combination of a flexible mattress supporting surface comprising a mesh wire fabric composed of a multiplicity of flexible wire cables extending generally longitudinally of the bed 35 and interconnected with each other by clips to form a mesh surface; a multiplicity of coil springs adjacent each end of the frame to support said fabric, each of said springs including an anchor loop secured to the end frame member and a free 40 loop at the opposite end of the spring, connections between the individual cables of the mattress supporting fabric and the free loops of said springs including a twisted pigtail joint between two adjacent flexible wire cables of the mattress 45 supporting fabric to form a loop between the adjacent cables of the fabric; the twisted pigtail connections between the cables extending into the coils of the individual springs, so that the free ends of the cables are entirely surrounded 50 and protected by the convolutions of the coil spring, together with transverse supporting bands extending across the bed between the longitudinal side members and coil springs at each end of each of said bands whereby the bands are 55 resiliently secured to the side frame members; the edge cable of the fabric being secured to the side frame member adjacent the anchor end of the coil spring and the second and third cables being secured to the free loop of said spring, so 60 that the spring extends across one unit of the mesh surface and so that no longitudinal cable contacts the convolutions of the spring.

2. In a bed spring including longitudinal side 65 frame members and transverse end frame members, the combination of a flexible mattress supporting fabric including a multiplicity of wires extending generally longitudinally of the bed; and joined to each other to form a mesh surface, together with transverse supporting springs extending between the longitudinal side frame members and the fabric so that the fabric is resiliently secured to the side frame members; each of said springs including an anchor loop secured to the side frame and a free loop secured 70 to the fabric; the structure being characterized 75

by the arrangement of the side wires of the fabric wherein the edge wire is secured to the side frame member adjacent the anchor loop of the coil spring and the second and third wires are secured to the free loop of said spring.

3. In a bed spring including longitudinal side frame members and transverse end frame members, the combination of a flexible mattress supporting fabric consisting of a multiplicity of flexible wire cables extending generally longitudinally of the bed and supported by coil springs at each end, a multiplicity of clips extending between adjoining cables of the fabric alternately, to unite the individual longitudinal cables and form a mesh surface; together with transverse supporting bands extending across the bed between the longitudinal side members and coil springs at each end of each of said bands whereby the band is resiliently secured to the side frame members; each of said springs including an anchor loop secured to the side frame and a free loop secured to the band; the structure being characterized by the arrangement of the side cables of the fabric wherein the edge cable is secured to the side frame member adjacent the anchor loop of the coil spring and the second and third cables are secured to the free loop of said spring, so that the spring extends across one unit of the mesh surface and so that no longitudinal cable contacts the convolutions of the spring.

4. In a bedspring construction having longitudinal side frame members and transverse end frame members, a flexible mattress including a plurality of cables extending generally longitudinally of said bed, means joining said longitudinally extending cables to provide a mesh surface, transverse supporting springs extending between the side frame members and the mesh surface whereby said surface is resiliently supported by the side frame members, said springs having an anchor loop secured to the side frame and a free loop secured to the mesh surface, means to affix the edge cable to said spring adjacent the anchor end thereof, and the second and third cables being supported by the free loop of said spring whereby the spring extends across one unit of the mesh surface so that the cable elements are held from contact with the convolutions of the spring.

5. In a bedspring including longitudinal side frame members and transverse end frame mem-

bers, the combination of a flexible mattress supporting surface comprising a mesh wire fabric composed of a multiplicity of flexible wire cables extending generally longitudinally of the bed and interconnected with each other by clips to form a mesh surface; a multiplicity of coil springs adjacent each end of the frame to support said fabric, each of said springs including an anchor loop secured to the end frame member and a free loop at the opposite end of the spring, connections between the individual cables of the mattress supporting fabric and the free loops of said springs including means between two adjacent flexible wire cables of the mattress supporting fabric to form a loop between the adjacent cables of the fabric; said last named means extending into the coils of the individual springs, so that the free ends of the cables are entirely surrounded and protected by the convolutions of the coil spring, together with transverse supporting bands extending across the bed between the longitudinal side members and coil springs at each end of each of said bands whereby the bands are resiliently secured to the side frame members; the edge cable of the fabric being secured to the anchor end of the coil spring and the second and third cables being secured to the free loop of said spring, so that the spring extends across one unit of the mesh surface and so that the cables are held from contact with the convolutions of the spring.

6. In a bedspring construction having longitudinal side frame members and transverse end frame members, a flexible mattress including a plurality of cables extending generally longitudinally of said bed, means joining said longitudinally extending cables to provide a mesh surface, transverse supporting springs extending between the side frame members and the mesh surface whereby said surface is resiliently supported by the side frame members, said springs having an anchor loop secured to the side frame and a free loop secured to the mesh surface, clip means within the anchor loop for securing the edge cable to side frame member, and a second clip means within the free loop to support the second and third cables whereby the spring extends across one unit of the mesh surface so that the cable elements are held from contact with the convolutions.

NATHAN C. GOLDBERG.
